U.S. PATENT DOCUMENTS

The ornamental design for a magnetic jewelry clasp, as shown
and described.

DESCRIPTION

FIG. 1 is a top, front perspective view with a portion of
unclaimed environmental structure shown;

FIG. 2 is a bottom, front perspective view thereof;

FIG. 3 is a front view thereof;

FIG. 4 is a top, front perspective view thereof, but in a closed
position;

FIG. 5 is a side view thereof, shown without the unclaimed
structure;

FIG. 6 is the opposite side view of the clasp of FIG. 5;

FIG. 7 is a front view of the clasp of FIG. 5;

FIG. 8 is a rear view of the clasp of FIG. 5;

FIG. 9 is a top view of the clasp of FIG. 5; and,

FIG. 10 is a bottom view of the clasp of FIG. 5.

The broken lines shown in the drawings represent environmental
structure and unclaimed portions of the design and
form no part thereof.
